METHOD OF WEAVING PILE FABRICS

Francis P. Groat, Bloomsburg, Pa., assignor to
The Magee Carpet Company, Bloomsburg, Pa.,
a corporation of Pennsylvania

Application June 1, 1950, Serial No. 165,535

13 Claims. (Cl. 139—39)

1

This invention relates to pile fabrics and method of making the same.

It is an improvement on the method disclosed in my prior application filed December 28, 1949, Serial Number 135,444, now Patent No. 2,590,608, and particularly relates to loop pile fabrics or loop and tuft pile fabrics wherein some of the rows of loops have loops of different height. In my prior application a method is disclosed for weaving pile fabrics on a wire loom wherein a plain pile wire and a low shank knob wire are employed to form the rows of loop pile and a cutting wire intermediate the plain and knob wires forms the rows of tufts. If an all loop pile is desired the cutting wire is eliminated.

It is an object of the present method to employ a high cutting or plain wire, a medium height plain wire and a low shank knob wire, the wires being inserted in the fabric during the weaving of the same in the order named whereby a pile texture is produced having rows of low loops, rows of loops of different heights in juxtaposition to the rows of low loops and rows of tufts or high loops, the latter rows being spaced apart by at least three weft threads.

Other objects and advantages of the invention will be apparent during the course of the following description.

In the accompanying drawing forming a part of this specification and in which like numerals are employed to designate like parts throughout the same,

Fig. 1 is an exploded perspective view of a fabric being woven in accordance with the method, and

Fig. 2 is a fragmentary warpwise section of the woven fabric showing some of the wires withdrawn.

In carrying out the method a conventional Jacquard wire loom is employed wherein a series of pile wires are inserted in the fabric during the weaving process and after a desired number of the wires have been inserted they are successively withdrawn and re-inserted in the shed formed immediately following the last wire in a series. The backing of the fabric may be of any conventional construction but for the purpose of illustration I have shown a backing comprising upper and lower weft threads 5 and 6 bound together by sets of binder warps 7 and 8. The pile warps 9 extend between the upper and lower series of weft threads and stuffer warps 10, as shown in Fig. 2, are disposed beneath the pile warps.

As the pile warps 9 are selectively raised by the

5 Jacquard mechanism the pile forming wires are successively inserted in the fabric. In accordance with my improved method a high cutting wire 11 or high plain wire 12 is inserted in the shed of selected pile warps and then the warps are restored to the backing. A medium height plain wire 13 is inserted in the next shed of selected warps and then the warps are restored to the backing. A low shank knob wire 14 is inserted in the next shed of selected warps and then the warps are restored to the backing. After inserting the desired number of wires in the order mentioned, the first wire inserted is withdrawn and reinserted in the fabric in the usual manner. When a high cutting wire 11 is withdrawn the loops 15 formed thereon will be cut to form a row of tufts 16, or if a high plain wire 12 is used instead of the cutting wire the withdrawal of the wire will form a row of high loops. 10 Withdrawal of a medium height wire forms a row of loops 17 of less height than the rows of tufts or high loops 16. The low shank knob wire 14 is of the same construction as the knob wire described in my co-pending application Serial Number 135,445, now Patent No. 2,590,609, and has a very low shank with a knob 18 on the end of less height than the medium height wire 13. 15 When a knob wire 14 is withdrawn the loops 19 formed on the low shank will ride up and over the knob 18 thereby being raised in height, as at 20, to a height corresponding to the height of the knob. If the pile warps raised over the knob wire 14 were also selected to form loops over the medium height wire 13, the raising of the loops 19 on wire 14 by action of the knob 18 will pull 25 the pile warps to reduce those loops in the preceding row, as at 21, formed from the same pile warps. Thus the withdrawal action of the knob wire 14 serves to reduce the height of some of the loops in the preceding row of medium height loops to form a row of different height loops. 30 By this method a fabric is made having successive rows of tufts or high loops, rows of medium and low height loops and rows of low loops. By 35 selectively raising the pile warps over the different types of pile wires fabrics of various designs may be woven with the cut or high loops forming the design areas and the medium and low loops forming the background areas. In forming a tuft area the pile warps are not raised over the medium height or low wires leaving voids between the rows of tufts which are the equivalent of two rows of loops. These voids are completely concealed by splaying of the tufts. In 40 forming the background areas the rows of low

loops will have voids at spaced intervals but it will be observed these voids are opposite medium height loops of the preceding row so that when the fabric is beat up and the wires are withdrawn the medium height loops will bulge laterally and fill in the voids in the rows of low loops making it appear that each row has a full complement of loops and that some are high and some are low in each row. The textured effect produced by the method is new and attractive.

Having thus described my invention, I claim:

1. A method of weaving on a wire loom a pile fabric having a backing and plurality of pile warps which comprises selectively raising the pile warps over a non-cutting high wire and restoring them to the backing, then selectively raising the pile warps over a non-cutting wire of lesser height than the high wire and restoring them to the backing, then selectively raising the pile warps over a low shank noncutting wire having a raised portion on its end of less height than said second mentioned non-cutting wire and restoring them to the backing, and successively withdrawing said wires in the order named to form a row of high loops, a row of low and medium height loops and a row of low loops.

2. A method of weaving on a wire loom a pile fabric having a backing and plurality of pile warps which comprises selectively raising the pile warps over a cutting wire and restoring them to the backing, then selectively raising the pile warps over a non-cutting wire of less height than said cutting wire and restoring them to the backing, then selectively raising the pile warps over a low shank wire having a raised portion on its end of less height than said non-cutting wire and restoring them to the backing, and successively withdrawing said wires in the order named to form a row of tufts, a row of low and high loops the high loops being of less height than the tufts and a row of low loops.

3. A method of weaving on a wire loom a pile fabric having a backing and plurality of pile warps which comprises raising the pile warps in accordance with a pattern and restoring them to the backing to form successive weftwise rows of high, medium and low loops and raising the rows of low loops to a height less than the height of the medium loops while lowering the height of those medium loops formed of the same pile warps as the low loops.

4. A method as described in claim 3 wherein the rows of high loops are cut to form rows of tufts.

5. A method of weaving on a wire loom a pile fabric having a backing and plurality of pile warps which comprises raising the pile warps over a high wire and restoring them to the backing, then raising the pile warps over a medium height wire and restoring them to the backing, then raising some of the pile warps that were raised over the medium height wire over a low wire having a raised portion on its end of less height than the medium height wire and restoring them to the backing, and then successively withdrawing said wires in the order named whereby the loops on the low wire are raised in height while lowering the height of those loops in the preceding row formed of the same pile warps.

6. A method of weaving on a wire loom a pile fabric having a backing and plurality of pile warps which comprises raising the pile warps in accordance with a pattern and restoring them to the backing to form weftwise rows of high

loops with intermediate rows of low loops and medium height loops and raising the rows of low loops to a height less than the height of the medium loops while lowering the height of those medium loops formed of the same pile warps as the low loops.

7. A method as described in claim 6 wherein the rows of high loops are cut to form rows of tufts.

10. 8. A method of weaving on a wire loom a pile fabric having a backing and plurality of pile warps which comprises selectively raising the pile warps and restoring them to the backing to form successive weftwise rows of high, medium and low loops with the rows of low loops having voids at spaced intervals and raising the rows of low loops to a height less than the height of the medium loops while lowering the height of those medium loops formed of the same pile warps as the low loops and leaving the remaining medium loops opposite the voids in the rows of low loops unchanged in height.

9. A method as described in claim 8 wherein the rows of high loops are cut to form rows of tufts.

10. 10. A method of weaving a pile fabric on a wire loom which comprises inserting a high wire, a medium wire and low knob wire successively in sheds of selected pile warps, the knob of said knob wire being of less height than said medium wire, weaving the pile warps over said wires to form weftwise rows of high, medium and low loops, with the rows of low loops having voids at spaced intervals, and successively withdrawing said wires to raise the rows of low loops and reduce the height of those loops of medium height of the immediate preceding row of loops formed from the same pile warps to a height corresponding to the height of the raised low loops.

11. 11. A method as described in claim 10 wherein said high wire is a cutting wire.

12. 12. A method of weaving a pile fabric on a wire loom which comprises inserting a high wire into a shed of pile warps, weaving the pile warps over said wire to form a row of high loops, inserting into a subsequent shed of pile warps a wire of less height than said first-mentioned wire, weaving the pile warps over said second wire to form a row of medium height loops, inserting into a subsequent shed of selected pile warps a knob wire having a knob of less height than said second wire, weaving pile warps over said knob wire to form a row of low loops with voids at spaced intervals, successively withdrawing said wires whereby the loops on said knob wire are increased in height and those loops of the immediate preceding row of medium height loops formed from the same pile warps are reduced in height.

13. 13. A method as described in claim 12 wherein said first-mentioned wire is a cutting wire.
